**COMBINED SERVICE STATION AUXILIARY
BUILDING AND CANOPY**Elliot F. Noyes, New Canaan, Conn., assignor to
Mobil Oil Corporation

Filed June 10, 1974, Ser. No. 477,945

Term of patent 14 years

Int. Cl. D25—03

U.S. CL. D25—34

FIG. I is a front elevation view of a combined service station auxiliary building and canopy of my new design.

FIG. II is the right side entry elevation view of the building of FIG. I.

FIG. III is the left side elevation view of the building of FIG. I.

FIG. IV is the rear elevation view of the building of FIG. I.

FIG. V is the sectional view of the building shown in FIGS. I, II, III and IV taken on line V-V of FIG. I.

I claim:

The ornamental design for a combined service station auxiliary building and canopy, as shown and described.
